DESIGN FOR A FORK, &c.

SPECIFICATION forming part of Design No. 22,680, dated August 8, 1893.

Application filed June 26, 1893. Serial No. 473,897. Term of patent 7 years.

To all whom it may concern:

Be it known that I, SIDNEY SMITH, a citizen of the United States, residing at Bridgeport, in the county of Fairfield and State of Connecticut, have invented and produced a new and original Design for Forks and Like Articles; and I do declare the following to be a full, clear, and exact description of the same, reference being had to the accompanying drawings, forming a part thereof.

Figure 1 is a plan view of the upper or obverse side of a fork embodying my novel design, and Fig. 2 is a plan view of the back or reverse side of a fork embodying my novel design.

The leading feature of the design consists of a plain center at the widest portion of the handle, said plain center being encircled by conventional Rococo ornamentation.

1 denotes the center, which is plain, and

may be either flat or rounded, and 2 denotes conventional ornamental waves of so-called Rococo style. At the base of the handle I provide other ornamentation as at 3 of the same general character.

1. The design for a handle for forks, and like articles, substantially as shown and described.
2. In a design for a handle for forks, and like articles, the obverse substantially as shown 30 and described.
3. In a design for a handle for forks, and like articles, the reverse substantially as shown and described.

In testimony whereof I affix my signature in 35 presence of two witnesses.
